UNITED STATES PATENT OFFICE.

ISIDOR FLEISCHMANN, OF BROOKLYN, NEW YORK.

AUTOMOBILE-RADIATOR.

1,227,770.

Specification of Letters Patent. Patented May 29, 1917.

Application filed August 16, 1916. Serial No. 115,140.

To all whom it may concern:

Be it known that I, ISIDOR FLEISCHMANN, a citizen of Hungary, and a resident of Brooklyn, in the county of Kings and State of New York, have invented certain new and 5 useful Improvements in Automobile-Radiators, of which the following is a specification.

This invention relates to an automobile 10 radiator of novel construction which possesses a large capacity for the circulation of the cooling water, and effects a thorough cooling of such water. The invention further comprises novel and efficient means, for 15 removing any damaged section of the radiator without disturbing the remaining sections.

In the accompanying drawing:

Figure 1 is a perspective view of an automobile 20 radiator embodying my invention;

Fig. 2, a vertical longitudinal section on line 2—2 Fig. 3;

Fig. 3, a horizontal section on line 3—3

Fig. 2 with the flanges of the front plates 25 partly broken away;

Fig. 4, a vertical cross section on line 4—4

Fig. 5, a perspective view of one of the detachable cooling units, and

Fig. 6, an enlarged cross section through 30 a pair of adjoining units.

The radiator, as shown, is of the so-called "torpedo" type, being composed of two wings, that join at an acute angle. It comprises essentially, a pair of converging upper water chambers 2 having open bottoms, and a pair of correspondingly arranged lower water chambers 3 having open tops. At the rear ends the two chambers 2, 3 of 40 each wing abut against a common back plate 4, while at their forward ends all the four chambers abut against a common upright member 5, the whole forming a frame. Above this frame there is mounted a hood 6 45 that spans both of the wings and is furnished with a filling nozzle 7.

Between the water chambers 2, 3 of each wing are interposed a plurality of cooling units each composed of a front plate 8, a 50 rear plate 9, and a plurality of tubes 10, set into said plates, and adapted for the passage of the cooling air. The front plates 8 are considerably longer than the rear plates 9 (Fig. 5), and abut at their forward edges 55 against the upright member 5, while the rear

plates 9 of one wing will at their forward edges abut against the forward edges of the other wing. In this way, there will be formed, at the nose of the apparatus, an additional upright water chamber 11, which is devoid of all air tubes so as to retain its maximum capacity. This upright water chamber 11 communicates at its upper end with the converging front ends of the upper water chambers 2, at its lower end with the converging front ends of the lower water chambers 3 and at its inner end with the several units constituting the air-cooled members 8, 9, 10. The hot water from the motor cylinders is admitted to the top of chamber 11 (or to either one of the upper chambers 2) by inlet nozzle 12, and is withdrawn from either one of the lower chambers 3 by an outlet nozzle 13. In this way a circulation will take place, part of the water passing through the cooling units to be here subjected to the action of the air pipes, while part of the water will flow through the upright chamber 11, to be here cooled by the draft or cooling air currents induced by the motion of machine through space, the water being also free to flow directly between the upright chamber and the cooling units.

Thus it will be seen that the capacity of the radiator is large relatively to its size, while all of the circulating water will be thoroughly cooled.

The several cooling units are made removable from each other so that any one that may have become defective through collision or otherwise, may be replaced without disturbing the remaining perfect units. To this effect, the front plates 8, are provided with horizontal rearwardly extending flanges 14, while the rear plates 9 are provided with horizontal forwardly extending flanges 15, the flanges 14 with the construction shown, protruding beyond the flanges 15.

When the several units are fitted within the frame, the two flanges 14 of two adjoining units will overlie each other, as will also the flanges 15. By now soldering the overlying flanges together, the units will be connected in a water tight manner, the flanges furnishing an ample surface for the reception of the solder. When any one of the units is to be replaced, the solder is removed by the application of a soldering iron.

Though I have shown a number of cooling units to be incorporated into each wing of

the radiator, a single unit may be so employed, whenever the removable feature of the cooling members is not desired.

I claim:

5 An automobile radiator composed of a pair of converging upper water chambers, a pair of converging lower water chambers, and cooling members interposed between

said chambers, each cooling member being formed of a rear plate, a front plate projecting a distance beyond the rear plate, and a plurality of air tubes set into the plates, the forwardly projecting ends of the front plates forming an upright water chamber at the nose of the radiator.

ISIDOR FLEISCHMANN.
